INKSTAND

Frank M. Ashley, Great Kills, N. Y., assignor to
Lewis Gompers, trustee, New York, N. Y.

Application December 23, 1936, Serial No. 117,275

4 Claims. (Cl. 120—69)

My invention relates to inkstands.

The object of my invention is to provide an inkstand having a dip-tube formed to support a pen-holder which may serve as a closure for the inkwell, and to provide a cup for ink which is located directly below the dip-tube and holds a supply of ink at a predetermined level, with means for lifting ink from the well and delivering it to the cup in which the pen carried by the pen-holder rests.

A further object is to provide an inkwell which may be filled with ink without removing any of its parts.

A further object is to provide an inkwell in which the ink will not be forced from the well by changes in air pressure in the well, caused by heat expanding the air therein above the surface of the ink.

A further object is to construct an inkstand which has no parts which operate automatically and which is made from hard materials not affected by weather conditions whereby a stand may be provided that will last indefinitely without renewal of any part thereof.

Referring to the drawing which forms a part of the specification;

Fig. 1 is a perspective view of an inkstand embodying my invention.

Fig. 2 is a vertical sectional view of the stand illustrated in Figure 1.

10 indicates the body portion of an inkstand which may be made of glass or other suitable material, and is formed to provide a well 10' for ink.

15 The inner wall is vertical as illustrated at 11 and its upper open end is closed by a cover 12 which is held therein by a soft rubber gasket 13, or the cover may rest on the top of the stand by reason of its weight.

20 The cover is preferably formed with a central circular opening 14 in which is fitted a cup 15 the outer wall of which is cylindrical and which extends to a point near the bottom of the well 10'.

25 The cover 12 and cup member may be formed integral but I prefer to make them to fit together as shown in separable relation to permit the cup portion to be easily removed from the cover to allow for cleaning and easy filling of the well.

30 The upper end of the cup is formed to provide a dip-tube which is shaped to support a pen-holder while supporting a pen in the cup, and is indicated by 16.

35 The upper side of the cup is formed with openings 17—17 located just below the lower end of the dip-tube, and a saucer shaped dish 18 rests in the bottom of the well and is provided with a

central opening 19 the inner wall of which closely fits the cylindrical wall of the cup in sliding relation thereto and its rim is provided with a plurality of upwardly extending abutment members 20—20 etc. spaced around its periphery 5 which are positioned to abut the under side of the cover and position the openings in line with the upper side of the dish whereby ink lifted by the upward movement of the dish will flow therefrom thru said openings into the cup.

10 A rod 21 is connected to the dish and extends upwardly therefrom thru a hole 22 in the cover, and is provided with a handle or knob 23 by means of which the dish may be lifted.

I prefer to use hard vulcanized rubber for the 15 cover and other portions except the body portion 10 which may be made of glass or other suitable material.

The cup is filled by simply raising the dish by means of the rod 21, one or more times, the 20 surplus ink flowing back into the well when the cup is filled.

The well may be filled without removing the cup if desired or the cup may be removed from the well and the ink poured directly therein, as 25 will be readily understood.

Having thus described my invention I claim as new:

1. An inkstand comprising a body portion having a well for ink, a cover portion comprising a 30 cup for ink having a cylindrical outer wall extending to a point adjacent the bottom of the well, said cup having openings in its upper side wall leading into the cup, and a dish having an opening therein the wall of which fits the said 35 cylindrical wall of the cup in close sliding relation; the construction being such that the dish may be lifted and supply ink to the cup.

2. The construction defined in claim 1, together with; and a dip-tube located above the 40 cup formed to support a pen-holder with a pen carried thereby projecting into the cup.

3. An inkstand comprising a body portion having a well for ink, a cover portion comprising a cup carried thereby in separable relation, said 45 cup having a cylindrical outer wall extending to a point near the bottom of the well and having an opening in its upper side wall leading into the cup, a dish having an opening therein the wall of which fits the said cylindrical wall in sliding relation, and means for lifting the dish a predetermined distance in the well in the act of filling the cup with ink.

4. The construction defined in claim 3, together with; and a dip-tube formed in the upper 55 end of the cup.

FRANK M. ASHLEY.
